UNITED STATES PATENT OFFICE.

GILBERT S. COOK, OF ELLIS, NEBRASKA.

PUMP-COUPING.

1,186,885.

Specification of Letters Patent. Patented June 13, 1916.

Application filed August 4, 1915. Serial No. 43,632.

To all whom it may concern:

Be it known that I, GILBERT S. COOK, a citizen of the United States, residing at Ellis, in the county of Gage, State of Nebraska, have invented certain new and useful Improvements in Pump-Couplings; and I do hereby declare the following to be a full, clear, and exact description of the invention, such as will enable other's skilled in the art to which it appertains to make and use the same.

The present invention is directed to improvements in couplers for pump rods, and has for its object to so construct a device of this character that the pump rod of a wind-mill and piston rod of a pump can be easily and quickly coupled or uncoupled.

A further object of the invention is to provide a coupler of this type so constructed that the shock incident to the reciprocation of the wind-mill rod and pump rod will be absorbed, thereby preventing either of said rods from breaking.

With these and other objects in view, this invention resides in the novel features of construction, formation, combination and arrangement of parts to be hereinafter more fully described, claimed and illustrated in the accompanying drawing, in which:—

Figure 1 is a side elevation of the device. Fig. 2 is a rear elevation. Fig. 3 is a sectional view on line 3—3 of Fig. 1. Fig. 4 is a sectional view on line 4—4 of Fig. 1.

Referring to the drawing 1 indicates a plate, the lower end of which is formed with an enlargement 2, said enlargement being provided with spaced ears 3 which are provided with bearings 4, the purpose of which will appear later. The enlargement has a rectangular opening 5 formed therein for receiving the pump piston rod 6, the upper end of which passes through said opening and rests flush against the plate 1, and between the flanges 7 carried thereby, said rod

having perforations formed therein for engagement by the arm 8 of the U-bolt 9. The arm 10 of the bolt 9 slidably engages the bearings 4 formed in the ears 3, and is encircled by coil spring 11, which has one end engaged with one of the ears and the other end fixed to the arm in any suitable manner, said spring serving to retract the bolt so that the arm 8 thereof will bridge the opening 5 when engaged with the piston rod 6.

A resilient pawl 12 is supported by one of the ears 3 and is adapted to engage a notch 13 formed in the arm 11 of the bolt 9, and when engaged with said notch it will be noted that the arm 8 of said bolt will be disengaged from the pump rod so that the same can be readily removed. When it is desired to attach the pump rod it is only necessary to actuate the pawl to disengage the notch, whereupon the spring 11 will cause the bolt 9 to move inwardly, whereby the arm 8 thereof will engage the rod.

Formed integral with the plate 1 is a guide 14 in which slides a rod 15, the upper end of which is provided with a flanged plate 16, and to which is attached the lower end of the wind-mill pump rod 17. The lower end of the rod 15 is formed with a reduced portion 18 which slidably engages the bore 19 formed in the enlargement 2. A nut 20 is threaded on the rod 15, and is engaged by the lower end of the coil spring 21, which encircles the rod, and has its upper end engaged with the guide 14. A collar 22 is engaged upon the rod 15 and is engaged by the upper end of the coil spring 23, the lower end of which engages the guide 14. The spring 23 encircles the rod.

By providing the springs 21 and 23 it is obvious that jars occasioned by reciprocation of the wind-mill rod and pump piston rod will be absorbed, thus preventing injury to said rods, but at the same time permits the rods to reciprocate to perform their functions.

The pump piston rod 6 is provided with a reduced extension 24, and has adjustably mounted thereon a collar 25. Having its upper edge engaged with the collar 25 is a coil spring 26, which encircles the extension 24, and has its lower end engaged with the pump cylinder 27, said spring serving to absorb the jar incident to the reciprocation of the pump piston rod.

What is claimed is:—
A coupling of the class described consisting of a plate having an enlargement upon its lower end, and bearings carried by the enlargement, a pump rod, said enlargement having an opening formed therein for engaging the pump rod, a U-bolt having one arm slidably engaged in the bearings and the other in the enlargement, a spring carried by one of the arms for holding the other arm engaged with the pump rod, said

plate being further provided with a guide, a rod slidably engaged with the guide, coil springs encircling the rod on opposite sides of the guide and serving to yieldably connect the rod to the plate, and means carried by the rod for engaging a wind-mill rod.

In testimony whereof, I affix my signature, in the presence of two witnesses.

GILBERT S. COOK.
